US00D844063S

(12) **United States Design Patent** (10) **Patent No.:** **US D844,063 S**
(45) **Date of Patent:** **** Mar. 26, 2019**

(54) **GAMING MACHINE**

(71) Applicant: **AGS LLC**, Las Vegas, NV (US)

(72) Inventors: **Sigmund Lee**, Atlanta, GA (US); **Karl Frederick Zedell, Jr.**, Alpharetta, GA (US); **Rachel Calhoun Lewis**, Atlanta, GA (US); **Wei Gu**, Daly City, CA (US); **Ariel David Turgel**, San Francisco, CA (US); **Daniel Kendall Harden**, Palo Alto, CA (US)

(73) Assignee: **AGS LLC**, Las Vegas, NV (US)

(**) Term: **15 Years**

(21) Appl. No.: **29/631,063**

(22) Filed: **Dec. 27, 2017**

Related U.S. Application Data

(62) Division of application No. 29/540,241, filed on Sep. 22, 2015, now Pat. No. Des. 820,915.

CLAIM

The ornamental design for a gaming machine, as shown and described.

DESCRIPTION

FIG. 1 is a front perspective view from above of an embodiment of the claimed design;

FIG. 2 is a front elevation view of the claimed design of FIG. 1;

FIG. 3 is a rear elevation view of the claimed design of FIG. 1;

FIG. 4 is a first side view of the claimed design of FIG. 1;

FIG. 5 is a second side view of the claimed design of FIG. 1;

FIG. 6 is a top plan view of the claimed design of FIG. 1;

FIG. 7 is a bottom plan view of the claimed design of FIG. 1.

FIG. 8 is an enlarged view of the portion of FIG. 1 labeled FIG. 8; and,

FIG. 9 is an enlarged view of the portion of FIG. 2 labeled FIG. 9.

The broken lines showing portions of the gaming machine depicts the boundaries of the claimed design and form no part of the claim.

1 Claim, 6 Drawing Sheets
